UNITED STATES PATENT OFFICE

108,649

DESIGN FOR A BRACKET FOR SUPPORTING AN ELECTRIC IRON AND CORD

Anthony Savaglio, Chicago, Ill.

Application December 15, 1937, Serial No. 73,633

Term of patent 14 years

To all whom it may concern:

Be it known that I, Anthony Savaglio, a citizen of the United States, residing at Chicago, in the county of Cook and State of Illinois, have invented a new, original, and ornamental Design for a Bracket for Supporting an Electric Iron and Cord, of which the following is a specification, reference being had to the accompanying drawing, forming part thereof.

Figure 1 is a perspective view; and
Figure 2 is a side elevational view of a bracket
embodiment my new design.

I claim:

The ornamental design for a bracket for supporting an electric iron and cord, as shown.

ANTHONY SAVAGLIO.
